WALTER S. OGILVY, OF ELMHURST, NEW YORK, ASSIGNOR TO ALCO PRODUCTS, INCORPORATED, OF NEW YORK, N. Y., A CORPORATION OF DELAWARE

HEAT EXCHANGER BAFFLE

Application filed June 4, 1931. Serial No. 541,996.

This invention relates to heat exchangers, particularly those of the tubular type, wherein a baffle is employed transversely of the exchanger shell for dividing the interior of the shell into separate compartments. The object of the present invention is to provide an improved baffle construction which will embody means for effecting a liquid tight fit at all points of contact between its edges and the inner faces of the shell.

Heretofore, various methods have been employed for effecting a liquid tight contact between the edges of baffle plates and the inner faces of the heat exchanger shells in which they have been embodied, but for various reasons none of such methods have proven entirely satisfactory. Such methods have included: machining the shell to a smooth and accurate finish in its interior before inserting the baffle; providing the interior of the shell with longitudinal grooves into which the edges of the baffle were adapted to fit; constructing the shell in two separate longitudinal halves having extended flanges, and disposing the baffle between the halves of the shell and bolting the baffle to the flanges; and welding the baffle to the shell or casting the same integral therewith. All of the foregoing methods have proved either inefficient in that they failed to insure a liquid tight joint or were too expensive for practical use.

The instant invention provides a novel and improved baffle which embodies expanding means for effecting an efficient, liquid tight contact with the exchanger shell, which construction is characterized by simplicity, sturdiness, ease of removability, and low cost of manufacture.

The invention is illustrated in the accompanying drawings in which Fig. 1 is a longitudinal sectional view, on the line I—I of Fig. 2, of a heat exchanger with the baffle of the instant invention applied thereto; Fig. 2 is a transverse section on the line II—II of Fig. 1; Fig. 3 is a plan view, partly in section, of the baffle of the instant invention on an enlarged scale; Fig. 4 is a side view of the baffle shown in Fig. 3; Fig. 5 is an end view of the baffle shown in Fig. 3 looking to the right; Fig. 6 is a sec-

tion on the line VI—VI of Fig. 3; Fig. 7 is a plan view, partly in section, of a modified form of baffle; Fig. 8 is a section on the line VIII—VIII of Fig. 7; Fig. 9 is a longitudinal section of parts of a heat exchanger with a second modified form of baffle applied thereto, one of the parts showing the baffle with one of its plates removed; Fig. 10 is a section on the line X—X of Fig. 9; and Fig. 11 is a partial transverse section on line XI—XI of Fig. 9.

The novel baffle of the instant invention is adapted to be applied to any ordinary type of heat exchanger. Such an exchanger is illustrated in Fig. 1, and comprises a cylindrical shell 1 having an inlet port 2, and an outlet port 3. A tube sheet 4 is provided at one end of the shell and an annular channel 5 is disposed adjacent the tube sheet. The channel is provided with an inlet port 6, an outlet port 7, a cover plate 8, and a transverse partition wall 9. The opposite end of the shell 1 is provided with a cover 10. A plurality of spaced parallel tubes 11 are held by the tube sheet 4 at one end, and are provided with a floating tube sheet 12, at their opposite ends, and a floating cover 13. Spaced, orificed, transverse, semi-circular baffle plates 14 are provided between the ends of the tubes on each side of the longitudinal baffle, the tubes passing through the orifices. The orifices are of sufficient diameter to provide a clearance around the tubes, also permitting the passage of liquid therethrough. A transverse baffle plate 14a is provided near the floating end of the tubes, and comprises a complete circular plate made of a heavier material than the semi-circular baffle plates. Tie-rods 15 are secured to the tube sheet 4, at one end, pass through the transverse baffle plates 14, and are secured to the end plate 14a by nuts 15a. Thimbles 15b are provided on the rods 15 between the transverse baffles, and serve to hold said baffles in their relative spaced positions. The shell, channel, tube sheets and covers are secured together, and provided with suitable gaskets where necessary in the usual manner, well known in the art.

The longitudinal baffle of the instant invention is adapted to be transversely disposed

across the interior of the shell so as to divide the same into separate compartments between the tube sheet 4 and the baffle plate 14a. The longitudinal baffle comprises two flat parallel plates 16—16 separated by bars 17, which are longitudinally disposed therebetween, the bars and plates being held rigidly together by rivets 18. At one end of the plates 16, yokes 19 are secured. The yokes comprise side members 20, which are joined to the oppositely disposed plates 16—16, and a cross member 21 connecting the side members and provided with a slot 22. Openings 14b are provided in the transverse baffle plate 14a, the yokes 19 extending through said openings.

Between the plates 16—16 and near the longitudinal edges of the same, expander bars 23—23 are disposed. The expander bars are of such thickness as to be easily slidable between the plates 16—16, and are formed on their inner edges with wedge-shaped projections 24. In the preferred embodiment of the invention the projections are formed as integral parts of the expander bars, but in practice they may be formed as separate parts and secured to the expander bar if desired, in any suitable manner. The ends of the expander bars, remote from the channel end of the exchanger, are provided with threaded projections 25 which extend through the slots 22 in the yokes 19 being permitted a slight lateral movement therein. Washers 26 are provided on the projections 25 and expander nuts 27 are fitted on the threaded projections adjacent the washers. Adjacent the inner sides of the expander bars 23 between the plates 16—16 spacers 28 are provided, and adjacent the wedge-shaped projections 24, rollers 29 are provided. The rollers 29 are held by bolts 30, which pass therethrough and through the plates 16—16 and which permit rotation of the said rollers. Between the plates 16—16 and adjacent the outer edges of the expander bars 23, follower strips 31 are disposed, the strips being of such thickness as to permit their free sliding between said plates. At the outer edges of the strips 31, strips of packing 32, are disposed, the packing comprising a fiber composition or any other well known suitable material. When the baffle is inserted within the shell 1, the packing rests between the outer edges of the follower strips of the baffle and the inner surface of the shell. A strip of packing 33, similar to the strip 32, is disposed between the ends of the plates 16—16 and the tube sheet 4 in a transverse groove which is provided in said tube sheet adjacent the end of the baffle. The opposite ends of the plates 16—16 make contact with the inner face of the transverse baffle plate 14a, and when the nuts 15a on the tie-rods 15 are drawn up the longitudinal baffle is forced in the direction of the tube sheet 4, thereby compressing the pack-

ing strip 33 and effecting a liquid tight joint with the tube sheet. By tightening the expander nuts 27, the expander bars 23 will be drawn in the direction of the floating tube header, and the wedge-shaped projections 24, bearing against the rollers 29, will cause an outward movement of the expander bars, together with the follower strips 31, which in turn will press tightly against the packing strips 32 and thus effect a liquid tight contact between the outer edges of the follower strips and the inner faces of the shell. The pressure against the packing will effect a distortion of the same so that it will be enlarged at its edges and fill the spaces between the ends of the plates 16 and the inner faces of the shell thus providing a seal which prevents the passage of liquid into the space between the plates. As aforescribed the slots 22 permit a slight lateral movement of the projections 24, so that the outward movement of the expander bars will not be interferred with.

The baffle may be removed together with the tubes and tube sheets by simply removing the shell cover 10 and floating cover 13, and then turning the expander nuts 27 in reverse direction, until they make contact with the floating tube header 12 whereupon the expander bars 23 will be moved in the direction of the tube sheet 4, thus relieving the pressure on the packing strips 32, and permitting the tube bundle and baffle to be withdrawn as a unit through the channel end of the shell, the channel and its cover having been, of course, first removed from the shell. The extensions 25 being to the outside of the tubes and beyond the end of the shell, the nuts 27 are readily accessible for turning.

In Figs. 7 and 8, there is illustrated a modified form of baffle which is similarly constructed to the form hereinbefore described except that in this instance an expander bar construction is provided on one side only of the baffle. The edge of the opposite side of this baffle is simply provided with a strip of packing 34, to be compressed between said edge of the baffle and the inner side of the shell, to effect the desired liquid tight connection. The outward pressure against the packing on both sides of the baffle is in this instance afforded by the action of the single expander bar.

A further modified form of the invention is illustrated in Figs. 9 to 11 inclusive. Here the baffle comprises two flat parallel plates 35—35 which are secured together and held in their spaced relation by spacer collars 36, and rivets 37 which pass through said collars and said plates. A bar 38 is centrally disposed between the plates 35, and expander bars 39 are disposed between said plates on each side of the baffle near the outer edges of the same. The bars 38 and 39 are

of such thickness as to permit their free sliding movement between the plates 35-35. A series of semi-circular notches 40 are formed in the opposite edges of the bar 38, and a series of semi-circular notches 41 are formed 5 in the inner edges of the expander bars 39, the notches 41 being slightly in advance of the notches 40. Expander links 42 are disposed between the plates 35, on the opposite 10 sides of the bar 38, the respective ends of said links being semi-circular in shape and fitting within the notches 40 and 41. The links 42 like the bars 38 and 39 are of such thickness as to slide between plates 35. The 15 end of the bar 38 adjacent the floating tube sheet 43 is provided with a tapped portion 44 into which is fitted a threaded spindle 45. The spindle 45 is provided with a collar 46 adjacent the inner side of the tube sheet 43. In this instance the tube sheet 43 is provided 20 with a central orifice 47 and the floating cover 13' is formed with an inwardly extending integral sleeve 49, through which orifice and sleeve the spindle 45 extends. A releasing 25 nut 50 is provided near the end of the spindle outside of the cover 13' and the end 51 of said spindle is squared. Notches 52 are provided in the outer edges of the expander 30 bars 39. Rows of the spacer collars 36 are provided near the outer edges of the plates 35-35, passing through said notches. The expander bars, while being permitted free 35 transverse movement, are held against longitudinal movement by the spacers. At the fixed tube sheet end of the exchanger the plates 35 are secured to the tube sheet by lugs 53 which are secured to the plates by spacer rivets 37 and to the tube sheet by studs 54. A strip of packing 55 is disposed between 40 the end of the baffle and the fixed tube sheet to effect a liquid tight connection. Adjacent the outer edges of the expander bars 39 and between the plates 35-35, follower strips 56 are disposed and between the outer edges of 45 the follower strips and the inner face of the exchanger shell, strips of packing 57 are provided.

In assembling the modified form of baffle, the plates 35 are bolted to the fixed tube sheet 50 4 as aforescribed, the strip of packing 55 having been previously disposed between the end of the baffle and the fixed tube sheet. The square end of the spindle 45 is then turned and, the collar 46 bearing against the floating tube sheet 43, the bar 38 is moved 55 in the direction of the fixed tube sheet and an outward movement of the expander bars 39 is thereby effected so as to exert pressure on the strips of packing 57 and effect a tight connection between the outer edges of the baffle and the inner wall of the shell. This modified form of baffle may be removed from the shell with the tubes and tube sheets as a 60 unit by turning the spindle 45 in reverse direction thereby causing the collar 46 to leave

the floating tube sheet and the reversing nut 50 to make contact with the floating head cover and the continued turning of the reversing nut 50 and the spindle effecting the movement of the bar 38 toward the floating tube sheet 70 thereby relieving the pressure on the packing 55 and permitting the baffle together with the tubes and tube sheets to be withdrawn from the shell as a unit through the channel end of the shell, the channel and its cover and 75 the covers 10' and 13' having been first removed from the shell.

It will be apparent from the foregoing description that the instant invention provides novel and improved baffles which are simple 80 and sturdy of structure and of low cost to manufacture, and which at the same time afford an efficient and reliable means for effecting fluid tight contacts between their edges and the inner sides of heat exchanger shells. While there has been hereinbefore described specific embodiments of the instant invention it will be understood that many and various changes and modifications in form and details of structure may be made without departing 85 from the spirit of the invention and that all and any such changes and modifications as fall within the scope of the appended claims are contemplated as a part of the instant invention. 90

The invention claimed and desired to be secured by Letters Patent, is:

1. A baffle for a heat exchanger shell comprising a pair of spaced parallel plates; an adjustable member disposed between said plates at one side thereof; means for effecting transverse outward movement of said member with relation to said plates when said member is moved in a longitudinal direction to effect an expansion of the width of the baffle; and means for longitudinally moving said member with relation to said plates. 100

2. A baffle for a heat exchanger shell comprising a pair of spaced parallel plates; a member disposed between said plates adapted upon longitudinal movement with relation to said plates to move outwardly at the sides of said plates to increase the width of the baffle; a yoke at one end of said plates; a spindle connected to an end of said member 115 and extending through said yoke; and a nut engaging said spindle adjacent said yoke and adapted when turned to effect the longitudinal movement of said member.

3. A baffle for a heat exchanger shell comprising a pair of parallel plates; means disposed between said plates holding the same in fixed spaced relation; a longitudinal member slidably disposed between said plates adjacent the edges of one side of same; a wedge-shaped projection disposed on the inner side of said longitudinal member; a roller adjacent said projection secured to said plates between the same; and means for longitudinally moving said member, whereby the engage- 120 125 130

ment of said projections with said rollers will effect the outward movement of said member, to increase the width of said baffle.

4. A heat exchanger apparatus comprising a shell; a plurality of tubes disposed therein; tube sheets connected to the ends of said tubes; a transverse baffle near one end of said tubes having orifices formed therein through which the said tubes pass; a longitudinal baffle interiorally dividing said shell into compartments between one of said tube sheets and the transverse baffle; tie-rods connecting said transverse baffle to said tube sheet; and means on said tie-rods for effecting an adjustment of said transverse baffle to move the same in the direction of the tube sheet to effect a tight connection between the end of said longitudinal baffle and said tube sheet.

5. A heat exchanger apparatus comprising a shell; a plurality of tubes disposed therein; tube sheets connected to the ends of said tubes; a transverse baffle near one end of said tubes having orifices formed therein through which the said tubes pass; a longitudinal baffle interiorally dividing said shell into compartments between one of said tube sheets and the transverse baffle; tie-rods connecting said transverse baffle to said tube sheet; means on said tie-rod for effecting a longitudinal adjustment of said transverse baffle to move the same in the direction of said tube sheet to effect a tight connection between the end of said longitudinal baffle and said tube sheet; and means for laterally expanding said baffle to effect a tight connection between the sides of the same and the inner face of the shell.

6. A heat exchanger apparatus comprising a shell; a plurality of tubes disposed therein; tube sheets connected to the ends of said tubes; a transverse baffle near one end of said tubes having orifices formed therein through which said tubes pass; a longitudinal baffle interiorly dividing said shell into compartments between one of said tube sheets and said transverse baffle; means for effecting an adjustment of said transverse baffle to move the same in the direction of the tube sheet to effect a tight contact between the end of said longitudinal baffle and said tube sheet; an adjustable member operably engaged with said baffle adapted when moved in a longitudinal direction to extend laterally outward from said baffle to effect an expansion in the width of said baffle and to effect a tight connection between the sides of the baffle and the inner face of the shell; and means for longitudinally adjusting said adjustable means.

7. A heat exchanger apparatus comprising a shell; a plurality of tubes disposed therein; tube sheets connected to the ends of said tubes; a transverse baffle near one end of said tubes having orifices formed therein through

which said tubes pass; a longitudinal baffle disposed in said shell dividing the same into compartments and extending from one of said tube sheets to the transverse baffle, said longitudinal baffle comprising a pair of spaced parallel plates and a member disposed between said plates adapted upon longitudinal movement with relation thereto, to extend outwardly at the side of said plates to increase the width of the baffle and effect a tight connection between the same and the inner face of the shell; a yoke secured to the end of said plates adjacent the transverse baffle and extending therethrough; a spindle connected to the end of said member and extending through said yoke; and a nut engaging said spindle adjacent said yoke and adapted when turned in one direction to effect the longitudinal movement of said adjustable member in one direction to effect the outward movement of said member, and adapted when turned in the opposite direction to effect the longitudinal movement of said member in the opposite direction.

8. A baffle for a heat exchanger shell comprising a pair of spaced parallel plates; longitudinal members disposed between said plates at the opposite sides of the same adapted to move laterally with relation to said plates to extend outwardly from the edges thereof to effect an expansion of the width of the baffle; and movable means disposed between said members, means for operating said movable means to control the lateral movement, of said longitudinal members.

9. A baffle for a heat exchanger shell comprising a pair of spaced parallel plates; longitudinal members disposed between said plates at the opposite sides thereof adapted for lateral movement with relation to said plates, to extend outwardly from the edges thereof, to effect an expansion of the width of said baffle; a member disposed between said plates intermediate the laterally movable members; links connecting said intermediate member and said laterally movable members adapting said intermediate member when moved longitudinally to effect the lateral movement of said laterally movable members.

10. A heat exchanger apparatus comprising a shell; a plurality of tubes disposed therein; tube sheets connected to the ends of said tubes; a baffle longitudinally disposed in said shell comprising a pair of parallel plates; means holding said parallel plates in fixed spaced relation; an adjustable longitudinal member disposed between said plates adapted to move laterally with relation thereto for effecting a tight connection between the baffle and the shell; a member disposed within said plates adapted for longitudinal movement with relation thereto; connecting links between the last said member and said laterally movable member, adapt-

ing the latter to be moved outwardly upon movement of the longitudinally movable member in one direction; means connecting one end of the said plates to the adjacent tube sheet; and means connecting an end of said longitudinally movable member and the adjacent tube sheet for adjusting said longitudinally movable member to actuate said laterally movable member.

11. A heat exchanger apparatus comprising a shell; a plurality of tubes disposed therein; tube sheets connected at the ends of said tubes; covers for the tube sheets; a baffle longitudinally disposed in said shell comprising a pair of parallel plates; means holding said parallel plates in fixed spaced relation; an adjustable longitudinal member disposed between said plates adapted to move laterally with relation thereto for effecting a tight connection between the baffle and the shell; a member disposed within said plates adapted for longitudinal movement with relation thereto; connecting links between the last said member and said laterally movable member adapting the latter to be moved outwardly upon movement of the longitudinal member in one direction, one end of said longitudinally movable member being tapped; a spindle fitted in said tap having a collar formed thereon adjacent said tube sheet, said spindle passing through said tube sheet, and through said tube sheet cover, and being squared at its outer end; means connecting one end of the said plates to the adjacent tube sheet; and a nut near the end of said spindle, whereby upon the turning of said spindle in opposite directions the said longitudinally movable member may be moved in respective opposite directions to effect the inward and outward movement of said laterally movable member.

12. A heat exchanger comprising a shell; a transverse wall at one end of the shell; a longitudinal baffle detachably sealed along its longitudinal edges to the inner face of the shell and at one end to the transverse wall; and adjustable means engaging the opposite end of the baffle for pressing said first end against said transverse wall and for detachably holding said end in pressed engagement with said wall.

13. In combination with a heat exchanger having a shell, a baffle plate disposed within said shell having sealing means positioned along the edges thereof, a member mounted for longitudinal movement carried by said baffle plate, means for moving said member, and means engaging said member whereby at least one of said sealing means is moved laterally upon the longitudinal movement of said member, to effect a seal between said sealing means and said shell.

14. A baffle for a heat exchanger shell comprising a pair of spaced plates, an adjustable member disposed between said

plates, means for effecting transverse outward movement of said member with relation to said plates, said means comprising longitudinally movable means and means for moving said longitudinally movable means. 70
